THROWING MACHINE

Joseph P. McHugh, Pawtucket, R. I., assignor, by
mesne assignments, to Industrial Machine Cor-
poration, a corporation of Delaware

Application March 22, 1937, Serial No. 132,423
Renewed March 11, 1940

5 Claims. (Cl. 57—79)

This invention relates to new and useful im-
provements in apparatus for producing improved,
fully thrown lustrous yarn.

The term "lustrous yarn" as employed herein
5 is intended to embrace such yarns as raw silk,
rayon or artificial silk, spun silk, spun rayon, or
yarn made from any of the above fibers as well
as so-called synthetic pigment yarn.

The primary object of this invention is to
10 provide a machine of extremely low manufac-
turing cost which is adapted to fully throw yarn
formed from a plurality of single ends, or the
like, in a single spinning operation and form
therefrom final headless packages which are
15 ready to enter fabric forming machines.

A further important object of the invention is
to provide a machine of the above mentioned
type which will form its final packages with a
20 single series wind and with the packages on all
of the spindles of the machine being wound
synchronously so as to be completed simultane-
ously without any variation as to size or shape
and with a uniform amount of yarn.

A still further important object of the inven-
25 tion is to provide mechanism which will effect
stoppage of the entire machine upon breakage
of any single end being fed to a package.

Another object of the invention is to provide
30 independent tensioning mechanism for each
single end and with each tensioning mechanism
being operable to effect stoppage of the complete
machine as a result of breakage of its respective
single end.

A further object of the invention is to provide
35 a machine of the above mentioned type which is
constructed with a suitable number of spindles
so as to permit it to be operated with sufficient
economy to constitute a practical commercial
device and notwithstanding the fact that the en-
40 tire machine is stopped by the breakage of, and
remains idle during the splicing of, any single
end in the machine.

A further feature of this invention is to so
construct and arrange the various instrumen-
45 talities of a lustrous yarn throwing and final
package building machine that the various
spindles may be mounted to partake of angular
movement only, and no stop motion mechanism
for disconnecting the drives to the individual
50 feed rolls and the spindles need be provided.

An additional object of the invention is the
provision of a magazine feed for the several
single ends to prevent the stoppage of the ma-
chine when the supply of thread is exhausted on
55 any bobbin or other supply holder; stop motion

mechanism responsive to breakage of any single
end strand and to the action of the traverse
mechanism upon completion of the packages
on the spindles for stopping operation of the en-
tire machine; a novel form of overhead creel 5
and strand tensioning mechanism; improve-
ments in the drive for the rolls employed to feed
the doubled single ends; and an extremely
simple and efficient traverse motion for effecting
a single cycle building of the packages. 10

Other objects and advantages of the invention
will be apparent during the course of the follow-
ing description.

In the accompanying drawings forming a part
of this specification and in which like numerals 15
are employed to designate like parts throughout
the same:

Figure 1 is a side elevational view of the throw-
ing and package building machine embodying
this invention; 20

Figure 2 is an end elevational view of the
machine disclosed in Figure 1;

Figure 3 is a detail end elevational view of
the single end supply means and tensioning
mechanism disclosed in the upper portions of 25
Figures 1 and 2;

Figure 4 is a detail top plan view of the mecha-
nism disclosed in elevation of Figure 3;

Figure 5 is a detail longitudinal sectional view 30
of a supply bobbin or spool holding pin;

Figure 6 is a detail sectional view of the means
employed for removably securing a bobbin hold-
ing pin to a creel bar;

Figure 7 is a fragmentary elevational view,
partly in section, disclosing the feed roll mecha-
nism for one pair of spindles, a portion of a 35
spindle, and a spinner ring operatively associated
with said spindle;

Figure 8 is a detail elevational view illustrat-
ing the gear drive for the feed rolls; 40

Figure 9 is a fragmentary sectional view illus-
trating the supporting mechanism for the ring
spinner rails;

Figure 10 is a detail side elevational view of
the form of traverse mechanism embodied in 45
this machine; and

Figure 11 is a top plan view of the traverse
mechanism disclosed in Figure 10.

Referring particularly to Figures 1 and 2, it
will be seen that the main frame of the machine 50
is formed primarily by the two end castings 15
and 16. These end castings preferably are of
identical construction. The casting 15 is dis-
closed in end elevation in Figure 2 and will be
described in detail. The bottom portion of the 55

casting is formed with suitable legs 17 which are provided with adjustable feet 18 usable to effect leveling of the machine frame. The legs 17 are braced by a bar 19 which functions as a support for certain portions of the mechanism, as will be described at a later point. Above the brace bar 19, a second brace bar 20 is provided for reinforcing the leg portions 17. Above the leg portions, the casting is formed as a reduced head portion 21 having a relatively large opening 22 to accommodate certain portions of the driving mechanism for the machine.

The two end castings 15 and 16 are interconnected and maintained in proper spaced relation by means of longitudinally extending rails. Figures 1, 2, 10, and 11 disclose two bottom rails 23 and 24 which are suitably connected to the lower brace bars 19 of the casting legs 17. These longitudinally extending rails 23 and 24 function primarily as supports for the traverse mechanism, to be described in detail at a later point. Above the lower traverse supporting rails 23 and 24 is positioned a spindle rail 25. This spindle rail is best illustrated in Figures 1 and 2 as being permanently connected to the end castings 15 and 16 in a manner to prevent any movement of the spindle rail relative to the main frame of the machine.

Above the spindle rail and connected to the head portions 21 of the end castings is a single rail 26 (see particularly Figures 1 and 7) which extends longitudinally of the machine and is positioned in the vertical central plane of the entire machine frame. This rail functions as a support for the feed rolls and a part of the driving mechanism for the rolls, as will be described in detail at a later point.

The upper extremities of the head portions 21 of the end castings have connected thereto a longitudinally extending rail 27 which is clearly illustrated in Figures 1, 2, 3, and 4 as constituting a support for the single end supply creels and tensioning devices. A reinforcing tie rod 28 is illustrated in Figures 2 and 3 as extending longitudinally of this top rail 27.

An overhead creel structure and single end tensioning mechanism is provided and is best illustrated in Figures 1, 2, 3, and 4. Figures 3 and 4 illustrate the top rail 27 as having secured thereto a suitable number of transversely extending bracket members 29. These bracket members extend transversely of the machine frame and are arranged in longitudinal parallelism. As will be clearly developed as the description of this machine proceeds, one of these brackets 29 is provided for each spindle of the machine. Both ends of each one of the brackets 29 are provided with upstanding apertured ears 30. One end of each transverse bracket 29 has suitably secured to its apertured ear 30, as by means of a bolt and nut device 31, a creel bar 32. Formed at suitably spaced intervals throughout the length of each creel bar 32 is a bearing opening 33 formed in a bearing enlargement 34 of the bar. Figures 3 to 6 best illustrate this structure. It will be noted from the disclosure of Figure 3 that these bearing enlargements are grouped in pairs with the axes of the bearing openings for each pair angularly arranged with respect to each other so that the said axes will converge at a point spaced transversely of the top of the machine frame and approximately at the opposite side of the frame.

Each one of these bearing openings 33 is designed to receive an enlarged hub portion 35

of a bobbin or spool supporting pin 36. This bobbin pin hub 35 is formed with an enlarged flange 37 at one end designed to bear against one face of the bearing enlargement 34 to restrict movement of the bobbin pin 36 through the bearing opening. The pin hub 35 is provided with an annular groove 38 in its periphery which is designed to receive a spring-pressed detent ball 39 mounted in an opening formed in the bearing enlargement 34. Figures 3 and 6 disclose the set screws 40 which back up the springs employed for forcing the detent balls into the pin hub grooves 38.

Figure 5 discloses each bobbin pin 36 as having mounted thereon a leaf spring member 41 which functions to frictionally retain a bobbin on the pin. This spring member 41 functions to prevent axial displacement of a bobbin from the pin and angular movement of the bobbin relative to the pin. It will be noted that the bobbin pins are to be inserted in the bearing openings 33 from the outer side of the creel bars 32 so that the bobbins or spools 42 will be positioned inwardly of the creel bars. The outer ends of the bobbin pins 36 are each provided with an enlarged, circumferentially grooved operating head 43 by means of which the various pins may be manipulated.

The arranging of the bobbin pins in angularly related pairs is for the purpose of accomplishing a magazine feed of single ends to the twisting and winding mechanism. Figure 3 very clearly illustrates the manner in which this magazine feed for each single end is accomplished. Each bobbin or spool is wound with a desired amount of surplus at the inner end of the strand with this surplus normally wrapped around the flange 44 of the bobbin 42. This surplus of the inner end will be designated by the reference character 45.

The upper pair of bobbins 42 at the left of Figure 3 is operating in the following manner:

The single end strand 46 is being taken from the second bobbin 42 through suitable tensioning mechanism, to be described at a later point. The surplusage 45 of the inner end of this second bobbin 42 has been knotted, as at 47, to the outer end of the first or top bobbin 42, and this surplusage 45 has been wound back on the top bobbin 42. The surplusage 45 of the inner end of the top bobbin 42 has been wound up on the groove of the operating knob 43 which forms a part of the upper or top bobbin pin 36. This surplusage is, therefore, held in readiness to be knotted to the outer end of the strand wound on the bobbin which will be positioned on the second pin 36 when the supply has been exhausted from the bobbin illustrated as being positioned on this second pin and the new bobbin has been substituted therefor.

The second set of bobbins illustrated in Figure 3 or the third and fourth bobbins illustrate this condition. The single end 46 is shown as being taken from the fourth bobbin 42 through its tensioning mechanism. The third bobbin from the top is illustrated as having had its supply completely exhausted. When this supply became exhausted, the feed of the single end 46 automatically transferred or changed from the third bobbin to the fourth bobbin. The fourth bobbin is illustrated as having the surplusage 45 of its inner end wrapped around the grooved knob 43 of its spindle. The operator of the machine, as soon as it is noted that the third bobbin has been exhausted, will substitute a filled

bobbin and will knot the surplusage 45 of the fourth bobbin to the outer end of the supply on the new bobbin substituted for the exhausted bobbin. Bobbins three and four, therefore, will 5 assume the condition represented by bobbins one and two. This magazine feed of single ends overcomes the necessity of stopping the machine, in a manner to be fully described at a later point, when the supply of single ends becomes exhausted on any one bobbin.

For the purpose of maintaining a comparatively large supply or quantity of single ends in advance of the feed rolls, to be described in detail at a later point, the creel bars have been 15 mounted on the top of the machine frame, and the single ends being fed to a spindle on one side of the frame come from bobbins mounted on a creel bar located on the opposite side of the frame. The single ends, therefore, extend across 20 the top of the frame to tensioning device located at the opposite side of the frame and then up to a condenser and down to the feed roll for the spindle to which the single ends of any one creel are being fed.

25 The remaining end of each bracket 29, therefore, has suitably fastened to its upstanding apertured ear 30 a tension bar designated in its entirety by the reference character 41. Each one of these tension bars consists of angularly arranged plates 48 and 49. These plates are interconnected and maintained in proper, spaced, angular relation by means of a suitable number of straps which are electrically insulated from one or both of the plates 48 and 49. These plates 30 have suitably connected to their lower ends the wires 50 and 51, respectively, which form a part 35 of the circuit of an electric stop motion mechanism to be described in detail at a later point.

The plate 49 has formed therein a series of 40 longitudinally spaced apertures 51a with one of these apertures being provided for each associated pair of bobbins carried by the diametrically opposed creel bar 32. These apertures 51a are provided for passing the single ends 46 through 45 the plate 49 to the tensioning devices which will be designated in their entirety by the reference character 52. This type of tensioning device has been disclosed and described in great detail in a copending earlier application Serial No. 50 112,150 filed Nov. 21, 1936, and for that reason will be described in this case only in sufficient detail to enable one skilled in the art to arrive at an understanding of its mode of operation.

Each tensioning device 52 consists of the co- 55 operating elements 53 and 54. The element 53 is rigidly secured to the plate 48 by means of the securing element 55. The tensioning element 54 is pivotally mounted upon the plate 48 by means of the pin 56. Each one of these tensioning elements 53 and 54 is formed from a strand of wire properly shaped to provide a main body portion or back member 57 with a plurality of loops or eyes 58 projecting from one side thereof. These loops or eyes 58 on the tensioning elements 60 53 and 54 are suitably spaced longitudinally of the main body or back members 57 and are arranged on the respective tensioning elements 53 and 54 so that the loops or eyes 58 of one element are staggered with respect to the loops or eyes 65 of the other element.

The tensioning element 54 has its inner end 59 extending in the form of a finger or contact element. This element 54, as has been previously stated, is pivoted on the pin 56. A spring is associated with the pivot portion of the tensioning

element 54 and functions to normally urge this element downwardly so that the contact finger 59 will engage the plate 49 to electrically connect the plates 48 and 49.

In Figure 3 the single ends 46 are illustrated 5 as extending through the guiding apertures 51a and threaded or laced through the loops or eyes 58 of their respective tensioning elements 53 and 54. Each single end 46 is threaded through the loops or eyes 58 of both tensioning elements 53 10 and 54 in the order in which they are successively arranged; i. e., first through the loop or eye of the tensioning element 53 and then through the next adjacent loop or eye 58 of the tensioning element 54. The single ends 46 upon leaving 15 the tensioning devices 52 extend upwardly of the tensioning bar 47 to a condensing device to be described at a later point.

These tensioning devices automatically function to maintain at all times a uniform tension 20 on all of the single ends 46 from the supply bobbins. Figure 3 illustrates the lower tensioning element 54 in the position it normally assumes during the feeding of a single end through the device. This lower tensioning element 54, however, is capable of assuming an infinite number 25 of positions which occur between the extreme upper and lower positions. When in its extreme upper position, all of the loops or eyes 58 for both of the tensioning elements 53 and 54 are in interlaced or overlapped relation. This lower tensioning element 54 may move downwardly from 30 this upper extreme position into its lower extreme position where the contact finger 59 engages the plate 49. 35

As stated above, the purpose of this tensioning mechanism is to assure at all times a uniform tension being imposed upon the single end strand being fed thereto. If the tensioning mechanism were not automatically variable, variations in 40 tension imposed upon the single end strand by variations in conditions under which the strand leaves the supply bobbin would not be compensated for. With this tensioning mechanism, as greater tension is imposed upon a single end 45 strand as it leaves its supply bobbin, the tension imposed upon that strand by its tensioning mechanism is lessened in direct proportion to the increase in tension at the bobbin. This lessening in tension imposed by the tensioning device 50 continues until no tension is provided by the mechanism, and if this action does not constitute a sufficient relief for the tension condition, the strand will break. When a strand breaks, the 55 lower tensioning element 54 drops into its extreme lower position with the contact device 59 engaging the plate 49 and, therefore, establishing an electric connection between the wires 50 and 51.

This variation in tension imposed by the devices 52 on the single end strands is accomplished by the movement of the lower tensioning element 54 relative to the element 53. In the positions illustrated at the right of Figure 3, the inner loops or eyes 58 of both elements 60 53 and 54 are substantially in register with each other so that the single end strand may pass substantially straight through the openings of these two eyes or loops. The remaining eyes or loops of the tensioning elements may be treated 65 as being arranged in successive pairs with each pair being formed by a loop or eye of each element 53 and 54. The disclosure shows the loops or eyes of successive pairs as being arranged in progressively greater spaced relation with re- 70 75

spect to each other. This variation in distance between the respective loops or eyes results in different degrees of tension being imposed on the single end strand by the respective pairs of loops or eyes. The greater the distance between the loops of a pair, the greater the degree of tension.

It will be apparent, therefore, that as the lower member 54 moves upwardly toward the upper 10 element 53, successive pairs of loops or eyes will be brought into alignment, and as a pair of opposed loops or eyes is brought into alignment, the tension formerly imposed upon the single end strand by this pair of loops is removed. The 15 removal of tension imposed upon a single end strand, by bringing into alignment pairs of opposed loops or eyes, may continue until all of the opposed pairs of loops or eyes are brought into alignment and the tension on this particular single end entirely removed.

For the purpose of bracing and steadyng the superstructure composed of the creel bars 32 and tensioning mechanism bars 47, an upstanding brace bar 60 is mounted on each end casting 25 15 and 16. The upper ends of these upstanding brace bars 60 are interconnected by a rod 61 which extends longitudinally of the machine frame and has suitably connected thereto a suitable number of transversely extending brace 30 arms 62 which are connected at their outer ends to the upper ends of the creel bars 32 and tensioning mechanism bars 47. The various single ends 46 leaving the tensioning devices 52 of any one tensioning bar 47 travel upwardly to and 35 through a condensing eye or thread guide 63 which is mounted upon and extends laterally outwardly of the upper end of its tensioning mechanism bar 47.

The doubled single ends leaving the condensing eyes 63 pass downwardly to feed roll devices and additional thread guides which will now be described.

Referring particularly to Figure 7, it will be seen that the previously described longitudinally extending feed roll rail 26 has mounted thereon a transversely extending bracket 64 which projects beyond both sides of the rail 26. By considering Figure 1, it will be seen that one of these bracket members 64 cooperates with a spindle on 40 each side of the frame. Both extremities of the bracket 64 are provided with apertured ears 65 intended to receive securing bolt and nut devices 66 by means of which feed roll supporting arms 67 are fastened to the opposite ends of the bracket 64. Each bracket, of course, is provided with a pair of feed roll supporting arms 67.

At a point intermediate its ends, each feed roll arm 67 has journaled therein a feed roll 60 shaft 68. On one side of the arm 67, the shaft 68 has suitably fixed thereon a feed roll 69. This feed roll is described in detail, as to its features of construction and mode of operation, in an earlier application Serial No. 112,150 filed 65 Nov. 21, 1936. For that reason it will receive only general attention. The feed roll preferably possesses a diameter of approximately five inches for the purpose of permitting a considerable quantity of doubled yarn to be maintained on its periphery. This considerable quantity of yarn permits a high twist to be placed in the yarn by allowing the twist to creep back from the spindle and ring spinner, to be described at a later point, around the periphery 70 of the feed roll. The feed roll is provided with 75

three peripheral channels 70 in which the doubled yarn is wrapped or wound around the feed roll.

The upper end of each feed roll supporting arm 67 has mounted thereon a thread spacing 5 and guiding element 71. This guiding element is formed with an inner loop portion 72 which receives the doubled strands or single ends from the condensing eye or guide 63 and directs these doubled single ends to the inner channel 70 of 10 the feed roll. The remainder of the guide element 71 is formed into a spiral 73 of cork screw formation. The spaces between the respective convolutions of this cork screw formation function as guides for directing and transferring the 15 doubled single ends as they leave the periphery of one channel 70 into and around the next adjacent channel. This cork screw formation, therefore, guides the doubled yarn into the successive channels 70 of the feed roll 69 and out 20 of the final or outer channel to a thread guide 74 adjustably supported on a pin 75 carried by an arm 76 which extends laterally outwardly of the feed roll supporting arm 67.

From the thread guide 74, the yarn extends 25 downwardly to the traveler 77 of the spinner ring 78 and forms the balloon 79, best illustrated in Figures 1 and 7. The spinner rings 78 for both sides of the frame are mounted upon ring rails 80. The two ring rails 80, one for each side 30 of the frame, are supported by the transversely extending angle brackets 81 which are supported and actuated by suitable traverse motion mechanism to be described in detail at a later point.

Each spinner ring has associated with the same, in the conventional manner, a spindle 82. The various spindles for both sides of the frame are journaled in the spindle rail 25 by means of bearing structures 83, see particularly Figures 1 and 2. These spindles 82 are mounted for angular movement only and are provided with the customary driving whirl 84.

The traverse or builder motion mechanism employed for effecting the desired vertical reciprocatory movement of the ring rails 80 is illustrated 45 in detail in Figures 10 and 11. Mounted on the transversely extending lower brace bar 19 of the end casting 15 are bearing brackets 85 which have journaled therein the drive shaft 86 which receives the power applied to the traverse or builder motion mechanism. This power is delivered to the shaft 86 by means of the worm wheel 87 driven in a manner to be described in detail at a later point. Suitably keyed to the drive shaft 86 is a heart cam 88. Stop collar 89 is fastened 50 to the shaft 86 to prevent axial movement of this shaft relative to its supporting bearings 85.

Journaled in bearing brackets 90 on the longitudinally extending rails 23 and 24 is a transversely extending shaft 91 which is arranged in 60 parallelism with the drive shaft 86.

Loosely journaled on the shaft 91 is a sleeve 92 having formed integrally therewith a laterally extending arm 93. At the outer end of this arm 93, a tubular boss 94 is formed and receives the 65 shaft 95, on one end of which is mounted the concentric truly cylindrical roller 96 which bears against and rides on the periphery of the heart cam 88. It will be seen, therefore, that the arm 93 is oscillated by the cam 88 when the latter is 70 driven and that the oscillatory movements of the arm 93 are of constant amplitude.

Formed integrally with the boss 94 of the arm 93 is an upstanding finger 97, to the extremity of which is pivotally connected a lever 98. The 75

outer end of this lever is pivotally connected to a link 99 which in turn is pivotally connected at its free end to a supporting arm 100 which is freely mounted upon the shaft 91. The pin 101 employed for connecting the link 99 to the arm 100 has journaled thereon a pawl 102 which is urged by the spring 103 into engagement with the peripheral teeth of the ratchet wheel 104.

This ratchet wheel is keyed to a second sleeve 105 loosely mounted on the shaft 91. A worm pinion 106 is keyed to or formed integrally with the sleeve 105 and meshes with a similar worm pinion 107 fastened to the extremity of a stub shaft 108 which is journaled in the bearing arms 109 projecting vertically from the oscillatable arm 93.

The remaining end of the stub shaft 108 has keyed thereto a worm gear 110 which meshes with a worm wheel 111 keyed to a short shaft 112 which is journaled in a bearing 113 formed integrally with the oscillatable arm 93. The shaft 112 has suitably keyed, or otherwise fastened thereto, a comparatively large builder or half-heart cam 114. The cam surface 115 of this builder cam terminates at its inner end in a stop shoulder 116. The cam surface 115 is unobstructed or uninterrupted from this stop shoulder 116 to its outer extremity 117.

The lever 98 has formed thereon an abutment 118 which is positioned to engage the head of an adjustable pin 119. The threaded stem of this pin is mounted in a fixed bracket 120 and is held in adjusted relation to this bracket by means of a set screw 121.

It will be appreciated that as the heart cam 88 rotates, it will cause the arm 93 to oscillate through a path of constant length or amplitude. As the oscillatable arm 93 is raised by the cam 88, the lever 98 will be moved upwardly until the abutment 118 engages the stop pin 119. Further upward movement of the lever 98 with the arm 93 will be checked or stopped by this pin 119. The lever 98, therefore, will pivot on the upstanding arm of finger 97 and will cause the pawl 102 to be moved downwardly. This downward movement of the pawl 102 will effect a small rotary movement of the ratchet wheel 104. The extent of rotary movement of this ratchet wheel may be varied by adjusting the location of the head of the stop pin 119 relative to the path of movement of the abutment 118 on the lever 98. Rotary movement of the ratchet wheel 104 will result in rotation of the worm pinion 106. This rotation of the pinion 106 will be transmitted through the meshing worm pinion 107 to the shaft 108 and from this shaft to the builder or half-heart cam 114 through the worm gear 110 and worm wheel 111 as well as the short shaft 112. It will be appreciated, therefore, that the oscillatory movement of the arm 93, resulting from rotation of the heart cam 88, will effect a step-by-step advancing movement of the half-heart or builder cam 114. This movement of the half-heart cam is in the direction of the arrow in Figure 10.

The periphery of the builder or half-heart cam 114 is engaged by a concentrically mounted, truly cylindrical roller 122 which is supported by a shaft 123 supported by the extremity of a lever 124 which is loosely journaled on the shaft 91. This lever 124 is employed for transmitting the motion produced by the traverse mechanism to the ring rails 80. It will be appreciated that this motion transmitting lever 124 partakes of movements which result from the action of the builder cam 114 being superimposed upon the action of

the heart cam 88. This movement of the motion transmitting lever 124 consists of an oscillatory movement produced by the heart cam 88 and a step-by-step changing of its starting location which results from the action of the builder or half-heart cam 114. When the roller 122 is in engagement with the stop shoulder 116 of the builder cam, the motion transmitting lever 124 is properly positioned to start the movement of the ring rails for beginning the building of packages on the various spindles. The ring rails are caused to traverse the spindles through strokes of constant amplitude as a result of the action of the heart cam 88. The builder or half-heart cam 114, however, advances the starting points of the traverse strokes of the ring rails and advances these strokes through successive steps until a single cycle build of the package has resulted in the production of a package of the desired length.

When packages of proper length have been produced on the spindles, the motion transmitting lever 124 has been moved until the abutment 125 carried on the same engages a switch arm 126 and moves this switch arm sufficiently to engage the contacts 127 connected to the stop motion circuit wires 50 and 51. When a circuit is closed to these wires 50 and 51 by engagement of the contacts 127, the entire machine will be stopped in a manner to be described at a later point.

After the machine has been stopped as a result of building complete packages, it becomes necessary to return the half-heart or builder cam 114 to its starting point. This is accomplished by means of a sprocket chain 128 which is trained over a sprocket wheel 129, keyed to the sleeve 105, and a second sprocket wheel 130 mounted on a shaft 131 which is supported in the bearing 132 carried by the end casting 15. A crank 133 is provided for driving the sprocket wheel 130. By lifting the pawl 102 out of engagement with the ratchet wheel 104, the sleeve 105 may be rotated in the opposite direction for causing the half-heart or builder cam 114 to be moved in the direction opposite to that indicated by the arrow appearing in Figure 10 and until the roller 122 engages the stop shoulder 116 at the inner end of the builder cam.

The mechanism employed for transmitting motion from the lever 124 to the ring rails 80 consists of a rod 134 which extends longitudinally of the entire frame. This rod is connected to the lever 124 by a pin and slot connection 124a which will allow for adjustment of the throw of rod 134 to shorten or lengthen the stroke of the ring rails. This rod 134 has pivotally connected to the same, at suitably spaced intervals, the two bell crank levers 135 which are supported by means of the depending bracket arms 136. The upper extremities of the bell crank levers 135 have journaled therein rollers 137 which engage the lower ends of vertically extending thrust rods 138. These thrust rods extend upwardly through slide bearings 139, carried by the spindle rail 25, for connection at their upper ends to the brackets 81 which support the ring rails 80 (see Figure 9).

The mechanism for driving the various spindles, the traverse or builder motion mechanism, and the feed rolls will now be described.

An electric motor 140 is suitably mounted upon the end casting 16 and drives a sprocket pinion 141 which has trained thereon a sprocket chain 142. This chain is trained over a sprocket wheel 75

143 keyed to a shaft 144 mounted on a bracket 145 also carried by the end casting 16. The shaft 144 also has mounted thereon two spaced belt pulleys 146 (only one of which is shown in Fig. 1) of equal diameter. These pulleys 146 are adapted to be selectively, singly clutched to the shaft so either one may be employed as the driving pulley while the other will act as an idler. This form of spindle belt drive is conventional for the Atwood 5B machine and permits changing the direction of rotation of the spindles for right or left twist.

A belt 147 is trained over the spaced pulleys 146 and extends longitudinally of the frame to be trained around the pulley 148 located at the opposite end of the frame. A small idler pulley 149 is adjustably mounted on a bracket 150 carried by the end casting 16 and is adjustable to properly tension the spindle driving belt 147 which is trained thereover. At suitable intervals, idler pulleys 151 are provided for maintaining the belt 147 in driving engagement with the whirls 84 of the various spindles.

For the purpose of causing any slippage of the belt employed for driving the spindles to result in a similar slippage in the drives for the traverse builder motion mechanism and the feed rolls, the drives for these two mechanisms are taken from the belt 147. The shaft 152 supports the pulley 148 around which the belt 147 is trained. This shaft is journaled in a long anti-friction bearing 152a fastened to the end casting by lateral arms 152b, best shown in Fig. 2. The upper end of this shaft 152 has keyed thereto a worm 153 which meshes with a worm 154. This worm 154 is keyed to a shaft 155 which also has keyed thereto a pinion 156. Meshing with this pinion is a shiftable pinion 157 journaled on the end of a bracket arm 158. The bracket arm 158 is maintained in the desired adjusted position by means of a clamping pin 159 which passes through the elongated aperture 159a of the bracket arm 158. Figs. 1 and 2 disclose an angular bracket plate 160 on which the bracket arm 158 is adjustably mounted by means of the pin 159. The pinion 157 meshes with the gear 161 when in its full-line position, which gear 161 is keyed to a shaft 162. This shaft 162 is supported in bearings carried by the bracket plate 160 and both of the end castings 15 and 16. The bracket arm 163 has journaled on its outer end an idler pinion 165. The bracket arm 163 is adjustably mounted on the bracket plate 160 by means of the pin 166 which is threaded in the bracket plate 160 and is passed through the slot 167 of the arm 163.

It often becomes desirable to change the direction of rotation of the spindles for producing either right or left twist. The direction of drive of the feed rolls and traverse or builder motion mechanism, however, must always be maintained the same. In the present machine, the direction of rotation of the spindles may be changed, as described above, by changing the clutched condition of the pulleys 146. With the spindle belt driven in one direction, the pinion 157 is positioned in mesh with the pinion 156 and gear 161 for effecting rotation of the gear 161 in the direction of the arrow appearing in Figure 8. The shaft 162, of course, will be rotated in the same direction as the gear 161. When rotation of the spindles is reversed, the shaft 162 may be rotated in the direction of the arrow appearing in Figure 8 by shifting the pinion 157 out of mesh with gear 161 and into mesh with the pinion 165

which in turn is adjusted to mesh with the gear 161. The shaft 162, therefore, is very suitable for use as a drive shaft for the feed rolls and the traverse or builder motion mechanism.

It often is desirable to change the amount of twist placed in the yarn being wound on the spindles. This result can be brought about by varying the ratio of drive from the shaft 155 to the shaft 162. The relative size and number of teeth of the pinion 156 and gear 161 may be changed, within permissible limits, to so vary the drive ratio. Because of the slot and pin mountings for the bracket arms 158 and 163, the pinions 157 and 165 may be adjusted to take care of changes in pinion and gear sizes.

The shaft 162 is supported at suitable points along its length by bearing brackets 169 (see Figure 7) and has mounted thereon a plurality of pinions 170. One of these pinions is provided for each transversely arranged pair of feed rolls 20 69. Figure 7 discloses one of these pairs of feed rolls as having the gears 170 and 171 mounted upon the short feed roll shafts 68. The gear 171 constantly meshes with the pinion 170 and the other gear 172. With this form of drive, both 25 of the feed rolls are driven in the proper directions, as indicated by the arrows in Figure 7.

Outwardly of the gear 161, the shaft 162 has mounted thereon a pulley or sprocket wheel 173 over which is trained a belt or sprocket chain 30 174. This belt or sprocket chain also is trained over a pulley or sprocket wheel 175 keyed to a shaft 176 which has a worm 177 keyed thereto and in mesh with the worm wheel 87 for driving the traverse or builder motion mechanism.

Due to the fact that this machine is built with a small number of units, ten or twelve spindles with their associated devices being considered a proper number, it has been determined that the entire machine can be stopped when any single 40 end breaks as well as when all of the packages are simultaneously completed and yet be an entirely satisfactory machine commercially.

The various single end tensioning devices 52 have been described as operating to electrically 45 connect or bridge between the wires 50 and 51 when any single end 46 of the entire machine breaks. The stop motion mechanism employed in this machine is of such a character that it will break the circuit to the electric motor 140 50 when the wires 50 and 51 are bridged or interconnected by any of the tensioning devices. It has also been pointed out that the traverse or builder motion mechanism effects a circuit closing action between the wires 50 and 51 when all 55 of the packages have been completed. The stop motion mechanism preferably consists of a motor starting box or rheostat with either an overload or no-voltage release mechanism which will operate when the wires 50 and 51 are electrically connected.

Figure 1 discloses very generally this type of automatic overload release starting box, which is designated by the reference character 178. This type of automatic control is very well known, and a great many different makes of the same can be purchased on the open market. Briefly, it consists of a manually controlled switch arm 179 which is moved into circuit closing position against a holding magnet 180. This magnet will function to hold the switch arm 179 in its circuit closing position until the circuit to the holding magnet is either short-circuited or broken. The wires 50 and 51 extend into this control box 178, and when these wires are interconnected or bridged at any of the tensioning devices or 75

the traverse or builder motion mechanism, the circuit for the holding magnet 180 will either be shorted or broken, in a well known manner.

It is to be understood that the form of this invention herewith shown and described is to be taken as a preferred example of the same and that various changes in the shape, size, and arrangement of parts may be resorted to without departing from the spirit of the invention or the scope of the subjoined claims.

Having thus described my invention, I claim:

1. In a machine for fully throwing lustrous yarn and building packages therefrom, a main frame, overhead single end supply means mounted on said frame, a plurality of spindles mounted on said frame for angular movement only, means for feeding the single ends to the spindles, spinner means movable relative to the spindles, traverse mechanism for actuating the spinner means, a prime mover, constant drive connections between the prime mover and the feeding means, the spindles, and the traverse mechanism, control means for the prime mover, and means for effecting actuation of the control means to stop the prime mover upon breakage of any single end being fed from the supply means and upon completion of the building of the packages on said spindles.
2. In a machine for fully throwing lustrous yarn and building packages therefrom, a main frame, a plurality of spindles mounted on said frame for angular movement only, magazine feeding means for uninterruptedly supplying a plurality of single ends to each spindle, means for feeding the single ends to the spindles, spinner means movable relative to the spindles, traverse mechanism for actuating the spinner means, a prime mover, constant drive connections between the prime mover and the feeding means, the spindles and the traverse mechanism, control means for the prime mover, and means for effecting actuation of the control means to stop the prime mover upon breakage of any single end being fed from the supply means and upon completion of the building of the packages on said spindles.
3. In a machine for fully throwing lustrous yarn and building packages therefrom, a main frame, overhead single end supply means mounted on said frame, a plurality of spindles mounted on said frame for angular movement only, means for feeding the single ends to the spindles, spinner means movable relative to the

spindles, traverse mechanism for actuating the spinner means, a prime mover, constant drive connections between the prime mover and the feeding means, the spindles and the traverse mechanism, control means for the prime mover, means for effecting actuation of the control means to stop the prime mover upon breakage of any single end being fed from the supply means, and means for effecting actuation of the control means to stop the prime mover upon completion of the building of the packages on said spindles.

4. In a machine for fully throwing lustrous yarn and building packages therefrom, a main frame, overhead single end supply means mounted on the frame, a tension device for each single end, a plurality of spindles mounted on said frame for angular movement only, means for feeding the single ends to the spindles, spinner means movable relative to the spindles, traverse mechanism for actuating the spinner means, a prime mover, constant drive connections between the prime mover and the feeding means, the spindles and the traverse mechanism, control means for the prime mover, means under the control of each one of said tensioning devices for effecting operation of said control means to stop the prime mover upon the breakage of any single end being fed from the supply means, and means under the control of the traverse mechanism for effecting actuation of said control means to stop the prime mover upon completion of the building of the packages on said spindles.

5. In a machine for fully throwing lustrous yarn and building packages therefrom, a main frame, single end supply means mounted on said frame, a spindle rail fixed with respect to the main frame, a double row of spindles journaled for rotary movement only on said spindle rail, means for feeding the single ends to the spindles, spinner means movable relative to the spindles, traverse mechanism for actuating the spinner means, a prime mover, drive connections between the prime mover and the feeding means, the spindles and the traverse mechanism, control means for the prime mover, and means for effecting actuation of the control means to stop the prime mover upon breakage of any single end being fed from the supply means and upon completion of the building of the packages on said spindles.

JOSEPH P. McHUGH.
